DUST-BAG STRUCTURE FOR VACUUM-CLEANERS.

1,377,721.

Specification of Letters Patent.

Patented May 10, 1921.

Application filed April 30, 1920. Serial No. 377,969.

To all whom it may concern:

Be it known that we, IRA J. OWEN and BERNARD J. BOUWMEESTER, citizens of the United States, residing at Grand Rapids, Kent county, Michigan, have invented certain new and useful Improvements in Dust-Bag Structures for Vacuum-Cleaners, of which the following is a specification.

This invention relates to improvements in dust bag structures for vacuum cleaners particularly adapted for the hand-propelled type.

The object of the invention is to provide a simple and effective structure in which the fabric will be effectively guarded and protected by the metal parts, and further to provide a structure of the class described which shall be very strong, staunch and durable.

Objects relating to details and economies of construction and operation will definitely appear from the detailed description to follow.

We accomplish the objects of our invention by the devices and means described in the following specification. The invention is clearly defined in the claims.

A structure which is a preferred embodiment of our invention is fully illustrated in the accompanying drawing, forming part of this specification, in which:

Figure I is a vertical longitudinal sectional elevation view through a combination vacuum cleaner and carpet sweeper, with one of our improved dust bags connected to the nozzle block, the nozzle being shown partially in full lines and the dust bag in its relation within the vacuum chamber being indicated in full lines.

Fig. II is a detail perspective view of the dust bag and nozzle block withdrawn from the vacuum chamber.

Fig. III is an enlarged detail sectional view taken on line 3—3 of Figs. I and II.

Fig. IV is a detail perspective view of the metal parts of our improved dust bag structure in exploded relation.

Fig. V is an enlarged detail longitudinal sectional view through our improved dust bag and gaskets in connection therewith, detached from the nozzle block, taken on line 5—5 of Fig. VI.

Fig. VI is an enlarged detail sectional view taken on line 6—6 of Figs. II and V.

Fig. VII is an enlarged detail sectional view taken on line 7—7 of Fig. V, showing details of the means for retaining the fabric at the inner mouth of the metal frame side.

In the drawing the sectional views are taken looking in the direction of the little arrows at the ends of the section lines, and similar numerals of reference refer to similar parts throughout the several views.

Considering the numbered parts of the drawing, 1 is the case of a vacuum cleaner of a usual form carried in the usual manner. 2 is the nozzle block carrying the dust box or bag 4 which is disposed in the vacuum chamber 3 of the said vacuum cleaner or sweeper. 5 is the gasket surrounding the same upon the nozzle block to close the front of the case.

The dust bag 4 is carried by the plate 6 which has protecting flanges 7 around the mouth of the dust bag and is perforated at 8 to receive the screws 9 securing the ends to the block 2. The gasket 5 is disposed upon this plate. The dust bag is provided with metal exterior channel-shaped sides 10 which have outwardly turned ends 11 spot welded to the plates 6 at 12 and spot welded at 13 to the flanges 7 (see Fig. IV). Cross bars 14 are at the inner end of the dust bag and are provided with flange 15 bearing the engaging portion 16 for engaging the cover. The cross bars 14 are spot welded at 17 to the outer ends of the side pieces 10 (see Fig. IV.).

The fabric bag 4 is open at both ends. The inner end is disposed within the mouth of the plate 6 and projects out beneath the same, extending within the flanges 7, 7. The sides of the bag are disposed within the channels of the side bars 10, and the outer end is folded over the outer end of the frame, as shown in Figs. V and VII. The flanges 15 are pressed down upon the fabric and clamp the same in position, as indicated in Fig. V. The retaining piece 20 with its flanged side 21 is disposed within the bag and fits snugly in position. The outwardly extending lug 22 is folded down upon the outer end of the side 10 and clamps the bag securely in position in that relation. Pro-

jecting ends 23, 23 are turned outwardly into engagement with the fabric and extend into the recesses 23', 23' that are formed in the plate 6 so that by this means the fabric 5 of the bag is securely held in place by the grip of the metal folded upon it, making a very staunch construction which can be removed with the nozzle block to discharge the contents therefrom, and is fully metal 10 bound and protected.

A cover 24 is provided, having side flanges 25 and end flanges 26 outturned to permit the same to be readily forced over the end of the bag. A depression 27 in the 15 side flange 25 is to receive the engaging projection 16 on the bar 14, already described.

A blade spring 28 is secured to the cover 24 by spot welds 29, 29 at each end and has a central projection 30 that contacts with 20 the rear or inner wall of the vacuum chamber 3, thereby forcing and clamping the same in position.

We have described the structure of our improved dust bag very much in detail and 25 we desire to claim the details of the same because of their superiority and because of the fact that the dust bag is practically protected from injury and the filtering surface utilized to a sufficient extent for the purpose. It will be observed that stitching and 30 glue and work of that kind are substantially eliminated from this structure, yet the same is exceedingly strong and effective. While we desire to claim the structure specifically 35 as shown, we also desire to claim the features broadly, as pointed out in the appended claims.

Having thus described our invention what 40 we claim as new and desire to secure by Letters Patent is:

1. In a dust bag structure, the combination with the nozzle block, of a base plate secured thereto, having projecting flanges at the discharge mouth from the said nozzle block, outer side pieces of flexible metal in channel form suitably joined to the said plate and flanges, cross bars connecting the outer ends of said side pieces together and provided with folding flanges thereon, a 45 dust bag disposed within said frame with its outer end embracing the outer end of said frame and retained by said flanges, and its inner end disposed within and beneath the flanged base plate, and retaining inner side bars conformed to the flanged outer sides with the ends folded over the fabric of the said dust bag, clamping the same in position, and with outwardly turned end lugs engaging within the mouth of the said base plate, all coacting substantially as described for the purpose specified.

2. In a dust bag structure, the combination with the nozzle block, of a base plate secured thereto, having projecting flanges 50 at the discharge mouth from the said nozzle

block, outer side pieces of flexible metal in channel form suitably joined to the said plate and flanges, cross bars connecting the outer ends of said side pieces together and provided with folding flanges thereon, a dust 70 bag disposed within said frame with its outer end embracing the outer end of said frame and retained by said flanges, and its inner end disposed within and beneath the flanged base plate, and retaining inner side 75 bars, all coacting substantially as described for the purpose specified.

3. In a dust bag structure, the combination with the nozzle block, of a base plate secured thereto, having projecting flanges 80 at the discharge mouth from the said nozzle block, outer side pieces of flexible metal in channel form suitably joined to the said plate and flanges, cross bars connecting the outer ends of said side pieces together and 85 provided with folding flanges thereon, a dust bag disposed within said frame with its outer end embracing the outer end of said frame and retained by said flanges, and its inner end disposed within and beneath the 90 flanged base plate, all coacting substantially as described for the purpose specified.

4. In a dust bag structure, the combination with the nozzle block, of a base plate secured thereto, having projecting flanges at 95 the discharge mouth from the said nozzle block, outer side pieces of flexible metal in channel form suitably joined to the said plate and flanges, cross bars connecting the outer ends of said side pieces together, a 100 dust bag disposed within said frame with its outer end embracing the outer end of said frame and its inner end disposed within and beneath the flanged base plate, and retaining inner side bars conformed to the 105 flanged outer sides with the ends folded over the fabric of the said dust bag, clamping the same in position, and with outwardly turned end lugs engaging within the mouth of the said base plate, all coacting substantially as 110 described for the purpose specified.

5. In a dust bag structure for vacuum cleaner, the combination with a nozzle block, of a flexible metal frame structure having outer channel bar sides, cross bars 115 at the outer ends forming the mouth of the bag, means for supporting the bag within the said channel bars, and a cap for the outer end of said dust bag, coacting as specified.

6. In a dust bag structure for vacuum cleaner, the combination with a nozzle block, of a flexible metal frame structure having outer channel bar sides, cross bars 120 at the outer ends forming the mouth of the bag, and means for supporting the bag within the said channel bars, coacting as specified.

7. In a dust bag structure for vacuum cleaner, the combination with the nozzle re- 125

movable block, of a fabric bag, a suitable framework for supporting said bag, and metal guard bars screwed to said nozzle block and surrounding and supporting the said bag, and removable therewith as specified.

In witness whereof, we have hereunto set

our hands and seals in the presence of two witnesses.
